WEATHERPROOFING STRUCTURE FOR WINDOWS

Filed April 28, 1930

UNITED STATES PATENT OFFICE

DAVID H. HARNLY, OF CHICAGO, ILLINOIS

WEATHERPROOFING STRUCTURE FOR WINDOWS

Application filed April 28, 1930. Serial No. 448,004.

This invention relates to a weatherproofing structure for windows and it is an object of this invention to completely seal the window to exclude the weather especially at the corners and at the ends of the junction of the upper and lower sections.

The invention comprises the novel structure and combination of parts hereinafter described and more particularly pointed out and defined in the appended claims.

In the accompanying drawings which illustrates a preferred form of this invention and in which similar reference numerals refer to similar features in the different views;

15 Figure 1 is a transverse section through a window embodying this invention;

Figure 2 is an enlarged vertical sectional view through the window taken upon the line II-II of Figure 1;

20 Figure 3 is an enlarged fragmentary sectional view at one of the corners illustrating the continuous character of the edge weather strip taken substantially upon the line III-III of Figure 1; and

25 Figure 4 is an enlarged sectional view taken upon the line IV-IV of Figure 2.

According to this invention, a weather strip is secured upon the window frame to engage the sides, the top and bottom of the two sections that constitute the window. This weather strip may be continuous for each section or may be suitably jointed at certain corners. The reference numeral 1 represents a U-shaped strip of felt or the like partially in-

35 cased in a metal sheath that is attached to the window frame and encompasses the bottom and sides of the lower window section 2 upon the inside. The reference numeral 3 indicates an inverted U-shaped strip of similar construction attached to the upper-half of the window frame and encompassing the upper sides and top of the upper window section 4 upon the inside.

40 The stiles of the two window sections are provided with vertical grooves 5 for receiving the unencased portions of the vertically extending portions of the weather strips. The lower rail of the lower section and the upper rail of the upper section are provided with exterior rabbets 6 (Figure 2) for respectively

abutting against the lower and upper horizontal portions of the weather strips 1 and 3. It will be noted in Figure 2 that the bottoms of the grooves 5 lie in the same plane as the bottoms 7 of the rabbets 6, and are co-planed. 55

The lower rail of the upper window section is also rabbeted as indicated at 8. A weather strip 9 partly encased is secured in the rabbeted portion 8 and the unencased portion of this strip extends into a rabbet 10 (Figure 2) formed in the upper rail of the lower window section when the sections are in closed positions. The casing of the weather strip 9 is preferably cut short at its ends so that the felt may project therebeyond as indicated at 11 in Figure 4 with the result that such exposed portions 11 will bear against the lower ends of the side strips of the U-shaped members 3 for effectively sealing the juncture of the two window sections. 70

When the two window sections are in closed position, the juncture thereof and the borders are effectively sealed against the weather. In the past, the upper and lower corners and the ends of the juncture between the sections was never effectively sealed as herein. It will be noted that the unbroken character of the weather strips 1 and 3 at 75 the corners and the fact that the same extends into grooved and rabbeted portions in the window sections, effectively seals the window at all points.

I am aware that many changes may be 80 made and numerous details of construction may be varied through a wide range without departing from the principles of this invention, and I, therefore, do not purpose limiting the patent granted hereon otherwise 85 than necessitated by the prior art.

I claim as my invention:

1. The combination with a window frame, 90 of a continuous weather strip extending upon the sides and one end thereof, a window slidably mounted in said frame and comprising a rail and stiles, said stiles having grooves for receiving said weather strip and said rail having a rabbet with its bottom in the plane 95 of the bottom of the grooves for receiving 100

the horizontal portion of said weather strip.

2. The combination with a window frame of a window consisting of an upper and lower section, having adjacent rails in their closed position, said rails being rabbeted, a weather strip secured in the rabbet of one rail and extending into the rabbet of the other rail, the stiles of the upper section being grooved, weather strips upon the sides of said window frame extending into said grooves and co-operating with the first mentioned strip to exclude the weather.

3. The combination with an upper window section having a lower rail and stiles, each stile having a vertical groove, a window frame, weather strips upon said frame extending into said grooves, a weather strip secured to said rail and abutting the lower ends of said weather strips upon the frame when the window section is in its closed position.

In testimony whereof I have hereunto subscribed my name at Chicago, Cook County, Illinois.
